[57] CLAIM

The ornamental design for a skirt fabric or similar article, substantially as shown and described.

DESCRIPTION

FIG. 1 is a plan view of a skirt fabric or similar article showing my new design, with the dot-dash lines indicating indeterminate width;

FIG. 2 is an enlarged fragmentary plan view, with the fragments broken for convenience of illustration; and FIG. 3 is a sectional view taken along line 3—3 in FIG. 2 and broken additionally between the two breaks shown in FIG. 2.

FIG. 1
